PROCESS FOR THE PREPARATION OF ALKYL
PHENYL PHOSPHORIC ACIDS AND THE
SALTS THEREOFHarry R. Gamrath, St. Louis, Mo., assignor to
Monsanto Chemical Company, St. Louis, Mo.,
a corporation of DelawareNo Drawing. Application May 1, 1950,
Serial No. 159,374

11 Claims. (Cl. 260—461)

1
This invention relates to alkyl phenyl phosphoric acids and the salts thereof; more specifically, this invention relates to an improved process for the preparation of certain alkyl phenyl phosphoric acids having the formula

wherein R_1 represents an alkyl radical terminating with a CH_2 group and containing from 6 to 18 carbon atoms and R_2 represents a phenyl radical. The novel process of this invention is also applicable for the salts of the above described alkyl phenyl phosphoric acids. It is an object of this invention to provide an improved commercially feasible process for the preparation of the above described alkyl phosphoric acids. Further objects will become apparent from the description of the novel process of this invention.

When one mol of an alkyl phosphoryl dichloride is added to an aqueous alkaline solution containing one mol of an alkali metal arylate, at least three possible reactions can take place. The phosphoryl derivative may hydrolyze to form the alkyl phosphoric acid, the phosphoryl derivative may react to give a mixture consisting of neutral alkyl diaryl phosphate and alkyl phosphoric acid or the alkyl phosphoryl dichloride may react to give alkyl aryl phosphoric acid. When the yield of alkyl aryl phosphoric acid is over 50% based upon the alkyl phosphoryl dichloride, then the reaction to produce this compound is the predominating of the three mentioned.

In a process for the preparation of alkyl phenyl phosphoric acids by the reaction of an alkyl phosphoryl dichloride with an alkali metal arylate in an aqueous alkaline solution, it was discovered that in the series where the alkyl group in the alkyl phosphoryl dichloride varies from methyl to octadecyl, the nature of the reaction is quite different when alkyl phosphoryl dichlorides wherein the alkyl substituent contains from 1 to 5 carbon atoms are utilized than when alkyl phosphoryl dichlorides wherein the alkyl substituent contains from 6 to 18 carbon atoms are utilized. When C_1 to C_5 alkyl phosphoryl dichlorides are utilized in such a reaction, the principal reaction is the formation of the alkyl diaryl phosphate. However, when C_6 to C_{18} alkyl phosphoryl dichlorides are utilized in such a reaction, the main reaction is the formation of alkyl phenyl phosphoric acids. This phenomenon is illustrated by the following table:

2
Yields obtained from one mol of alkyl phosphoryl dichloride and one mol sodium arylate

	Alkyl Phosphoryl Dichloride	Percent Yield of Alkyl Aryl Phosphoric Acid
10	Ethyl phosphoryl dichloride.....	29.2
	Butyl phosphoryl dichloride.....	46.0
	n-Hexyl phosphoryl dichloride.....	50.9
	2-Ethylhexyl phosphoryl dichloride.....	80.1
	n-Decyl phosphoryl dichloride.....	89.1
	Octadecyl phosphoryl dichloride.....	67.9

15 A preferred embodiment of this invention, therefore, consists in reacting a one molecular proportion of an alkyl phosphoryl dichloride wherein the alkyl substituent is an alkyl radical terminating with a CH_2 group and containing from 6 to 18 carbon atoms, with approximately a one molecular proportion of an alkali metal phenolate dissolved in an aqueous alkaline solution. After the reaction is complete, the alkyl phenyl phosphoric acid or its salt may be recovered from the reaction mixture by any method well known to those skilled in the art for the recovery of such type of phosphoric acids.

20 The following examples are illustrative of the novel process of this invention:

30

EXAMPLE I

n-Hexyl phenyl phosphoric acid

35 Into a glass reactor was charged 94.1 g. of phenol, 1,000 cc. of water and 80.0 g. of 50% sodium hydroxide. The aqueous sodium hydroxide solution was added slowly to the phenol-water mixture, keeping the reaction temperature below 25° C. Then the sodium phenate solution was cooled to about 15° C. and 218.6 g. of *n*-hexyl phosphoryl dichloride (obtained from one mol of POCl_3) was added during about 5 minutes, the reaction temperature being 16–22° C. The reaction mass was then stirred for an additional 12 hours at approximately 25° C. adding sodium hydroxide solution to keep the mass alkaline to phenolphthalein. About 181 g. of 50% sodium hydroxide solution was added during the stirring period.

40 45 After completing the reaction, the reaction mass was allowed to settle and the aqueous layer was separated from the neutral ester. The aqueous layer contained the sodium salt of *n*-hexyl phenyl phosphoric acid. The aqueous layer was then acidified with 600 cc. of concentrated hydrochloric acid to liberate the *n*-hexyl phenyl phos-

phoric acid. The acidified aqueous layer was allowed to stand over night, after which time an oil layer separated from the water layer, the oil layer was separated and steamed to remove volatiles and then dried by heating under reduced pressure. The weight of n-hexyl phenyl phosphoric acid thus obtained was 131.2 g. or a yield of 50.9% based on POCl_3 . It had the following physical properties:

Sp. gr. at 25°/25° C. 1.1245
Assay per cent 96.9

Analysis	Phosphorus, percent
Calculated for $\text{C}_{12}\text{H}_{19}\text{O}_4\text{P}$	12.0
Found	13.6

EXAMPLE II

2-ethylhexyl phenyl phosphoric acid

A 2-liter, round-bottom, three-necked flask was charged with 188.2 g. of phenol and 1120 cc. of water. 160 g. of a 50% sodium hydroxide solution was then slowly added to the mixture of phenol and water at such a rate and with constant cooling to maintain a reaction temperature below 25° C. To the cooled and constantly stirred sodium phenate solution was then added 494.4 g. of 2-ethylhexyl phosphoryl dichloride (obtained from two mols of POCl_3) over a period of about one hour, keeping the temperature of the reaction mass between 15° and 20° C. When about one-half of the 2-ethylhexyl phosphoryl dichloride had been charged, a 50% sodium hydroxide solution was added in sufficient quantity to maintain the reaction mass just alkaline to phenolphthalein. After the 2-ethylhexyl phosphoryl dichloride had been completely charged, the mass was stirred for an additional three hours, keeping the mixture alkaline during this period by the addition of sodium hydroxide. The mass was then allowed to settle, whereupon it separated into two layers.

The alkaline aqueous layer containing the sodium 2-ethylhexyl phenyl phosphate was separated from the neutral ester and extracted several times with benzene at 30–40° C. The benzene extracts were washed with a 1% sodium hydroxide solution and with water, and the washings were combined with the aqueous alkaline solution. After extraction, the aqueous alkaline solution was acidified with 78% sulfuric acid to liberate the 2-ethylhexyl phenyl phosphoric acid. The 2-ethylhexyl phenyl phosphoric acid was washed several times with water and then steamed at 100° to 105° C. to remove the benzene. The oil was washed once more with water and then dried by heating under reduced pressure. 372.7 g. of 2-ethylhexyl phenyl phosphoric acid was recovered, representing a yield of 65.2% based on POCl_3 , which had the following properties:

Sp. gr. at 25°/25° C. 1.0906

Analysis	Phosphorus, percent
Calculated for $\text{C}_{14}\text{H}_{23}\text{O}_4\text{P}$	10.8
Found	10.7

EXAMPLE III

2-ethylhexyl cresyl phosphoric acid

The sodium cresylate used in the preparation of 2-ethylhexyl cresyl phosphoric acid was made by charging a 5-liter flask with 486.5 g. of cresol (mainly a mixture of meta- and para-cresol, but also containing a small amount of ortho-cresol and xylenols), 2,500 cc. of water and 360 g. of 50% sodium hydroxide. After cooling the stirred sodium cresylate to about 10° C., 1,099.4 g. of 2-ethylhexyl phosphoryl dichloride (obtained from 4.5 mols POCl_3) were charged over a 35 minute period, the reaction temperature being maintained at 8–10° C. during this period. The reaction mixture was then warmed to about 55° C. in approximately one hour and sodium hydroxide solution added to keep the mass alkaline to phenolphthalein, and then stirring was continued for two hours more with the mass temperature in the range of 55°–75° C. The reaction mass was then allowed to cool and settle whereupon it separated into two layers.

The aqueous layer was separated from the neutral ester and acidified liberating an oil which was separated therefrom. The oil was steamed to remove dissolved cresol. After steaming, the oil was again dissolved in dilute sodium hydroxide solution and the solution extracted with benzene to remove any residual neutral esters. The aqueous alkaline solution was then acidified to liberate 2-ethylhexyl cresyl phosphoric acid which was separated and steamed to remove any dissolved benzene. The 2-ethylhexyl cresyl phosphoric acid was washed several times with water at 60–65° C. and the mass dried by heating under reduced pressure. 1080.8 g. of 2-ethylhexyl cresyl phosphoric acid were obtained representing a yield of 80.1% based on POCl_3 . The 2-ethylhexyl cresyl phosphoric acid thus obtained had the following properties:

Sp. gr. 25°/25° C. 1.0814

Analysis	Phosphorus, percent
Calculated for $\text{C}_{15}\text{H}_{25}\text{O}_4\text{P}$	10.3
Found	10.1

EXAMPLE IV

n-Decyl cresyl phosphoric acid

In accordance with the procedure described in Example III, n-decyl cresyl phosphoric acid was prepared utilizing the following reactants:

n-Decyl phosphoryl dichloride	g.	275
Cresol	g.	108.1
Water	cc.	1000
Sodium hydroxide (50%) (for sodium cresylate)	g.	80

In this case the sodium salt of n-decyl cresyl phosphoric acid was insoluble in the reaction mass. To facilitate the filtration operation, the somewhat sticky mass was mixed with an inert material and then the compound was liberated in an aqueous medium by acidification. The liquid n-decyl cresyl phosphoric acid was refined as usual.

From the charges listed above, 292.7 g. of n-decyl cresyl phosphoric acid were obtained representing a yield of 89.1% based on n-decyl phosphoryl dichloride. The n-decyl cresyl phos-

5

phoric acid thus obtained had the following properties:

Sp. gr. at 25°/25° C. 1.0424

Analysis	Phosphorus, percent
Calculated for C ₁₇ H ₂₀ O ₄ P	9.4
Found	9.1

EXAMPLE V

Octadecyl phenyl phosphoric acid

The octadecyl radical in the octadecyl phosphoryl dichloride utilized in this example was derived from 2-(1,3,3-trimethyl butyl)-5,7,7-trimethyloctanol.

383.3 g. of octadecyl phosphoryl dichloride (obtained from one mol POCl₃) were added to an aqueous solution of sodium phenate made from 94.0 g. of phenol, 1800 cc. of water and 80.0 g. of 50% sodium hydroxide. All of the octadecyl phosphoryl dichloride was added to the sodium phenate solution over a 35 minute period with the reaction temperature maintained at about 10° C. To complete the reaction, the mass was stirred an additional 5½ hours allowing the mass temperature to increase to about 40° C. During the stirring period, sodium hydroxide solution was added to keep the mass alkaline to phenolphthalein.

After the reaction was complete, the mass was allowed to stand whereupon solid sodium octadecyl phenyl phosphate separated. The solid sodium salt was separated by decantation and washed with water. The sodium octadecyl phenyl phosphate was then acidified with hydrochloric acid to liberate the very viscous octadecyl phenyl phosphoric acid. After washing with water, octadecyl phenyl phosphoric acid was dried by heating under reduced pressure. 289.3 g., representing a yield of 67.9% based on POCl₃, of octadecyl phenyl phosphoric acid was obtained having the following analysis:

Analysis	Phosphorus, percent
Calculated for C ₂₄ H ₄₄ O ₄	7.3
Found	7.7

EXAMPLE VI

Nonyl ortho-chlorophenyl phosphoric acid

In accordance with the procedure described in Example III, nonyl ortho-chlorophenyl phosphoric acid was prepared utilizing the following reactants:

	G.
Nonyl phosphoryl dichloride (a trimethyl substitute hexyl phosphoryl dichloride)	261
Ortho-chlorophenol	128.5
Water	1500
Potassium hydroxide (for potassium o-chlorophenate)	56.2

An excellent yield of substantially pure nonyl ortho-chlorophenyl phosphoric acid was thus obtained.

EXAMPLE VII

Tetradecyl 4-chloro-2-methylphenyl phosphoric acid

In accordance with the procedure described in Example III, tetradecyl 4-chloro-2-methylphenyl

6

phosphoric acid was prepared utilizing the following reactants:

	Parts by weight
Tetradecyl phosphoryl dichloride (the tetradecyl radical was derived from a branched chain tetradecyl alcohol derived from the polymerization of olefins)	165.5
Para-chloro-ortho-cresol	71.3
Water	1000
Potassium hydroxide (for potassium p-chloro-o-cresylate)	28.1

An excellent yield of substantially pure tetradecyl 4-chloro-2-methylphenyl phosphoric acid was obtained.

EXAMPLE VIII

2-methylpentyl o-nitrophenyl phosphoric acid

In accordance with the procedure described in Example III, an excellent yield of substantially pure 2-methylpentyl o-nitrophenyl phosphoric acid was obtained utilizing the following reactants:

	Parts by weight
2-methylpentyl phosphoryl dichloride	219
o-Nitrophenol	139
Water	2000
Sodium hydroxide (for sodium o-nitrophenate)	40

EXAMPLE IX

2-ethylhexyl 2,4,5-tribromophenyl phosphoric acid

In accordance with the procedure described in Example III, an excellent yield of substantially pure 2-ethylhexyl 2,4,5-tribromophenyl phosphoric acid was obtained utilizing the following reactants:

	Parts by weight
2-ethylhexyl phosphoryl dichloride	61.8
2,4,5-tribromophenol	83
Water	500
Sodium hydroxide (sodium 2,4,5-tribromo-phenate)	10

In addition to the alkyl phenyl phosphoric acids prepared in the preceding examples, the following alkyl phenyl phosphoric acids or the salts thereof are further illustrations, but not limitative, of alkyl phenyl phosphoric acids which may be prepared in accordance with the novel process of this invention:

- n-Hexyl cresyl phosphoric acid
- 2-ethylbutyl o-chlorophenyl phosphoric acid
- Heptyl 2,4-dibromophenyl phosphoric acid
- n-Octyl 4-bromo-2-methylphenyl phosphoric acid
- 2-ethylhexyl pentachlorophenyl phosphoric acid
- 6-methylheptyl 2,4,5-tribromophenyl phosphoric acid
- Nonyl p-ethylphenyl phosphoric acid
- Trimethylhexyl 3,5-dimethylphenyl phosphoric acid
- Decyl o-ethoxyphenyl phosphoric acid
- Undecyl p-isopropoxyphenyl phosphoric acid
- Dodecyl p-iodophenyl phosphoric acid
- Tridecyl m-cresyl phosphoric acid
- Tetradecyl m-fluorophenyl phosphoric acid
- Pentadecyl o-nitrophenyl phosphoric acid
- Hexadecyl p-chlorophenyl phosphoric acid
- Heptadecyl cresyl phosphoric acid
- Octadecyl p-bromophenyl phosphoric acid

In the above list of compounds the nonyl and dodecyl radicals may be derived, in addition to

the conventional sources, from the polymerization products of olefins, such as propylene or the dodecyl radical may be derived from the polymerization products of olefins, such as butylene. These alkyl radicals may also be derived from branched-chain primary alcohols prepared by the polymerization of olefins to form a branched-chain olefin, followed by the reaction with carbon monoxide and hydrogen (oxo process) to form a primary branched chain alkyl alcohol. Thus, a nonyl alcohol may be prepared from the polymerization of isobutylene to form an octene which may then be reacted with carbon monoxide and hydrogen to form a branched chain primary nonyl alcohol. Nonaldehyde may be prepared in a similar manner and may then be subjected to an aldol condensation to form a branched chain primary octadecyl alcohol. The alkyl radicals may also be derived from straight chain primary alcohols obtained by the hydrogenation of coconut oil and fats.

In the compounds of the invention, including those disclosed above, the cresyl radical may be ortho-cresyl, para-cresyl or meta-cresyl, for example, 2-ethylhexyl phenyl ortho cresyl phosphate, 2-ethylhexyl phenyl para-cresyl phosphate, or 2-ethylhexyl phenyl meta-cresyl phosphate. Also, the products of the invention may comprise mixtures of phosphate esters containing ortho, para and/or meta-cresyl radicals.

While specific quantities, reactants and reaction conditions have been set forth in the preceding examples, it is not intended that the novel process of this reaction be solely limited thereto, as substantial variation in the reactants, quantities of reactants and reaction conditions is possible. The alkyl phosphoryl dichlorides utilized in the novel process of this invention may be obtained by any convenient method. Preferably, they are obtained by reacting a one molecular proportion of a primary alkyl alcohol containing from 6 to 18 carbon atoms with an approximately one molecular proportion of phosphorus oxychloride, while maintaining a reaction temperature in the range of from about +2° C. to about +25° C. and while removing the hydrogen chloride formed until the reaction is substantially complete, and then continuing the removal of the hydrogen chloride formed at temperatures not in excess of about 50° C. The hydrogen chloride may be removed in any convenient manner, such as by blowing air through the reaction mixture or by running the reaction under a reduced pressure. Such a process for the preparation of alkyl phosphoryl dichlorides is described and claimed in my copending application Serial No. 135,311, filed December 27, 1949.

In the reaction between the alkyl phosphoryl dichloride and the alkali metal salt of a phenol, it is preferred that approximately equimolecular proportions of the reactants be utilized. Here again, however, some variation is permissible as it has been found that satisfactory results may be obtained by utilizing from about 0.9 mol. to about 1.1 mols. of the alkali metal arylate for each molecular proportion of the alkyl phosphoryl dichloride utilized. The temperature of this reaction may also be maintained over a wide range during the course of the reaction. Thus, reaction temperatures in the range of from about -10° to about +50° C. have been found to give satisfactory results. Preferably, however, the reaction temperature is maintained in

the range of from about -10° C. to about +25° C. Any of the alkali metal salts of a phenol may be utilized in this reaction. Typical of such salts are the sodium, potassium and the lithium salts. Similarly any phenol may be utilized in this reaction. Thus, the phenol may be unsubstituted or it may be substituted with one or more of the following illustrative substituents; halogens, such as chlorine, iodine, bromine and fluorine; nitro groups; alkyl groups, such as methyl, ethyl, propyl, isopropyl, butyl, sec.-butyl, amyl, etc; alkoxy groups, such as methoxy, ethoxy, propoxy, isopropoxy, butoxy, etc.

This reaction is carried out in an aqueous alkaline medium, that is, at a pH greater than about 7.0. Alkaline conditions may be maintained by the addition of any of the commonly used alkaline salts. Typical of such alkaline salts are the alkali metal hydroxides, such as, sodium hydroxide, potassium hydroxide, and lithium hydroxide, the alkaline earth metal hydroxides such as calcium hydroxide, magnesium hydroxide, etc. and the alkali metal carbonates, such as sodium carbonate, potassium carbonate, lithium carbonate, etc., and the alkaline earth metal carbonates, such as calcium carbonate, magnesium carbonate, etc. These alkaline salts may be added in a sufficient quantity at the beginning of the reaction to maintain alkaline conditions throughout the entire reaction or they may be added continuously or intermittently during the course of the reaction so as to maintain an alkaline reaction medium.

The alkyl phenyl phosphoric acid may be isolated or separated from the reaction mixture by any convenient method well known to those skilled in the art. Since the acid is present in the reaction mixture as its alkali metal salt, it may be separated therefrom as such, or it may be converted to the free acid and then separated therefrom. Furthermore, if desired, it may be separated from the reaction mixture as the free acid and subsequently converted to its salt. In some cases, the alkali metal alkyl aryl phosphates are insoluble in the aqueous reaction medium. These solids can be removed from the reaction mass by filtration which effects a separation from any neutral phosphate esters which may also be present. The solids can then be mixed with water and the phosphoric acid derivatives liberated therefrom by acidification. If the alkali metal salt is gelatinous and difficult to filter as is, the mass may be mixed with an insoluble, inert material, such as sand and then separated from the aqueous mass by filtration. Thereafter, the alkyl aryl phosphoric acid can be recovered in the usual manner. While some of the alkali metal salts of the alkyl phenyl phosphoric acid are solids, the alkyl aryl phosphoric acids which are obtained according to the novel process of this invention vary from mobile fluids to viscous liquids, as the alkyl group is increased from C₆ to C₁₈.

The alkyl aryl phosphoric acids prepared in accordance with the novel process of this invention may also be converted into metallic salts which have antioxidant activity for lubricating oils. The salts of the elements of group II of the periodic table are particularly useful. Such salts include the cadmium salt, barium salt, and the basic and neutral zinc salts of alkyl phenyl phosphoric acids.

What is claimed is:

1. In a process for the conversion of alkyl phosphoryl dichlorides to salts of alkyl phenyl phosphoric acid, said acid having the formula

wherein R_1 represents an alkyl radical terminating with a CH_2 group and containing from 6 to 18 carbon atoms and R_2 represents a phenyl radical, the step comprising reacting a one molecular proportion of an alkyl phosphoryl dichloride with an aqueous solution containing approximately a one molecular proportion of an alkali metal salt of a phenol, while maintaining the reaction mixture alkaline to phenol-phthalein.

2. In a process for the conversion of alkyl phosphoryl dichlorides to salts of alkyl phenyl phosphoric acid, said acid having the formula

wherein R_1 represents an alkyl radical terminating with a CH_2 group and containing from 6 to 18 carbon atoms and R_2 represents a phenyl radical, the step comprising reacting a one molecular proportion of an alkyl phosphoryl dichloride wherein the alkyl substituent is an alkyl radical terminating with a CH_2 group and containing from 6 to 18 carbon atoms, with an approximately one molecular proportion of an al-

kali metal salt of a phenol in an aqueous medium while maintaining the aqueous reaction medium alkaline to phenolphthalein.

3. The process as described in claim 2 wherein the alkyl phosphoryl dichloride is *n*-hexyl phosphoryl dichloride.

4. The process as described in claim 3 wherein the phenol is phenol.

5. The process as described in claim 2 wherein the alkyl phosphoryl dichloride is 2-ethylhexyl phosphoryl dichloride.

6. The process as described in claim 5 wherein the phenol is phenol.

7. The process as described in claim 5 wherein the phenol is cresol.

8. The process as described in claim 2 wherein the alkyl phosphoryl dichloride is *n*-decyl phosphoryl dichloride.

9. The process as described in claim 8 wherein the phenol is cresol.

10. The process as described in claim 2 wherein the alkyl phosphoryl dichloride is an octadecyl phosphoryl dichloride.

11. The process as described in claim 10 wherein the phenol is phenol.
